In France May 22, 1947

11 Claims. (Cl. 60—39.5)

1

This invention relates to gas engines with intake-discharge pressure differential increasing apparatus, and more particularly to improved gas engine apparatus for increasing the proportion of energy, particularly heat energy, which may be converted into work from the total amount of energy theoretically available in a gas or mixture of gases by increasing the inlet-discharge pressure differential in a new and improved manner.

It is, of course, well known that the proportion of the energy available in a gas or gaseous mixture which can be converted into useful work depends in part on the difference between the pressure of the gas or mixture delivered to the engine and the pressure against which the gas leaving the engine is discharged. In accordance with the present invention, an engine, preferably a turbine, itself embodies a novel arrangement by which this pressure differential is increased.

An object of the invention is to provide a gas engine such as a turbine constructed to increase the inlet-discharge pressure differential by arranging the driven element of the engine to discharge substantially at or immediately upstream of the neck or throat of a converging-diverging nozzle or the like.

In the accompanying drawings showing representative embodiments of the invention:

Figure 1 is an axial, sectional view of an apparatus embodying the invention and including a centripetal flow turbine;

Figures 2, 3, 4 and 5 are cross sections, respectively, on the lines II—II, III—III, IV—IV and V—V of Figure 1;

Figure 6 is a view similar to Figure 1 but showing a modification in which a supplemental compressor of the centrifugal type is embodied in place of the axial flow type compressor shown in Figure 1;

Figure 7 is a schematic, axial, sectional view of a modified construction;

Figure 8 shows two units embodying the invention in axial section coupled to act simultaneously in connection with a central turbine; and

Figure 9 is a schematic, axial, sectional view of an axial flow type turbine constructed in accordance with the invention.

In the illustrative embodiment of the invention shown in Figures 1 to 5, there is shown an apparatus comprising a stationary structure generally designated A and including a combined compressor and outer turbine housing 1, an inner turbine housing 2 within the housing 1, and a turbine housing section 3 shown as depending

from the lower end of the housing 1, all of the sections 1, 2 and 3 being in axial alignment. Mounted within the stationary structure A is a rotor generally designated B comprising a multi-stage compressor unit 4, a turbine rotor element 5, and a depending shaft 6, the rotor B being journaled in bearings 7 and 8. A supplemental compressor 9 has its rotor mounted on the lower end of the shaft 6.

10 The outer turbine housing 1 is formed with a plurality of axially aligned compressor stage housing sections 10, each containing a compressor rotor 11 forming part of the rotor structure B previously referred to. Hot gas from any available source—for example, an engine exhaust, the discharge of a system for cooling a mechanism or medium, or a combustion apparatus—is adapted to be introduced into the upper end of the compressor 4 through an inlet opening 12 so as to pass downwardly through the successive compressor stages and be compressed and then delivered to the turbine rotor 5 for operating the latter in a manner to be described later. During its passage through the successive compressor 20 stages, the gas introduced into the inlet opening 12 is cooled by air flowing through heat exchange passages 13 surrounding the compressor stages 10.

The turbine inner housing 2 is mounted inside of and in spaced relation to the outer turbine housing 1, being supported in the outer housing by ducts 14 which communicate with the heat exchange passages 13. The space 15 between the inner housing 2 and outer housing 1 is arranged to receive compressed and partially cooled gas from the compressor 4. The inner housing 2 is formed with an internal space 16 which receives air from the heat exchange passages 13 and the ducts 14.

40 The inner turbine housing 2 is formed to provide an annular section 17 surrounding the turbine rotor 5, the section 17 being provided around its periphery with inlets 18 through which compressed gas may enter the section 17 from the space 15. Radially inward of the space 17 are converging nozzles 19 arranged to discharge compressed gas inwardly to impinge upon and operate the turbine rotor 5. Spaced a little inwardly of the nozzles 19 are the exit edges of a plurality of blades 20 which provide other converging nozzles 21 through which air from the passages 13 and ducts 14, heated by heat exchange from the gas being compressed, is discharged to intermix with the gas discharged by the nozzles 19.

45 The discharge or outlet of the turbine, is defined by a section curved as at 22 so as to merge

with the throat 23 of a converging-diverging nozzle 24. At the zone of merging of the converging part 22 with the nozzle throat 23, is an annular stator nozzle 25 characterized by having the continuation or extension of one surface, e. g., its lower surface or lip, forming the wall of the converging part or throat 23 of the nozzle 24. Compressed gas, partially cooled by the air flowing through the heat exchange passages 13, flows from the space 15 through the annular nozzle 25 into the throat 23 of the converging-diverging nozzle 24, and passes downwardly through the nozzle 24. Because of the characterizing shape or arrangement of the annular nozzle 25 with respect to the converging-diverging nozzle 24, a low pressure zone or area created in the throat 23 is established immediately downstream of the discharge or downstream side of the turbine rotor 5. As a result, the pressure against which the rotor 5 discharges is reduced, thus increasing the inlet-discharge pressure differential and consequently increasing the capacity of the turbine 5 to convert energy in the gas entering at 12 into useful work.

In the embodiment shown in Figure 1, the mixture of air and gas passing downwardly through the nozzle structure 24 and expanding at the lower end thereof is recompressed by the supplemental compressor 9, and is then discharged at 26 for transmission to any desired apparatus or equipment for using the energy available in the recompressed mixture.

Figure 6 shows a construction the same as that shown in Figures 1 to 5, inclusive, with the exception that the Figure 6 construction includes a centrifugal type re-compressor 9^a in place of the axial flow type re-compressor 9 shown in Figure 1. The operation of the Figure 6 construction is generally similar to the operation described with reference to Figures 1 to 5.

The modified construction shown in Figure 7 includes a turbine housing 27, a rotor 28 mounted on a shaft 29 extending through a converging-diverging nozzle 30, and a centrifugal compressor 31, the turbine and compressor rotors and the shaft 29 being mounted in bearings 32-33.

The housing 27 includes a generally annular chamber 34 adapted to receive hot air or gas through an inlet connection 35. The chamber 34 is formed with inner surfaces 36-36^a which converge so as to lead to a restricted annular discharge passage 37 disposed at the periphery of the turbine rotor 28.

The housing 27 is formed at one side of the turbine rotor 28 (at the left as viewed in Figure 7) with a chamber 38 provided with an inlet opening 39 for the introduction of compressed air or gas from any suitable source, for example, from a compressor (not shown) driven by an extension of the shaft 29. The peripheral wall of the chamber 38 separates the chamber 38 from the annular chamber 34, and provides the converging inner surface 36 of the chamber 34 previously referred to. This peripheral wall is formed with a slot 40 which is so shaped that its downstream wall or surface, i. e., its wall or surface nearest the passage 27, merges with the converging surface 36 leading to the passage 37.

On the downstream side of the central plane of the rotor 23, that is, on the right hand side as shown in Figure 7, the housing 27 is formed with an annular chamber 41 having an opening 42 for the inlet of compressed air or gas from any suitable source, such as the source from which air is supplied to the inlet opening 39 leading to the

chamber 33. The peripheral wall of the chamber 41 separates the chamber 41 from the annular chamber 34, and provides the converging surface 36^a previously referred to as leading toward the passage 37. This peripheral wall is formed with a slot 43, the downstream wall or surface of which—that is, the wall or surface nearest the passage 27—merges with the associated surface 36^a converging upon the passage 37.

The inner wall 44 of the chamber 41 converges in a downstream direction from the passage 31 toward the axis of the turbine so as to merge with the neck or throat 45 of the convergent-divergent nozzle 30, which is constituted by the wall 44, the throat 45, and an expanding or diverging section 46. A straight section 47 is shown as being interposed between the diverging section 46 and the centrifugal compressor 31.

In operation, hot air or gas is delivered through the inlet opening 35 to the annular chamber 34 so as to flow through the nozzle passage 37 and impinge on the turbine rotor 28 for driving the latter, the shaft 29, and the supplemental compressor 31. Compressed air is delivered to the chambers 33 and 41 through the inlets 39 and 42, respectively, so as to flow through the slots 40 and 43 convergingly along the walls 36 and 38 of the chamber 34 in intermixture with the hot air or gas. The mixed hot air or gas and air from the chambers 34, 38 and 41 will be discharged on the downstream side of the rotor so as to pass through the neck or throat 45 of the converging-diverging nozzle 30, thereby creating a zone of reduced pressure in the throat 45 immediately downstream of and adjacent the rotor 28. In this manner the turbine exhaust pressure is reduced and the inlet-discharge pressure differential is increased. The gas and air mixture, recompressed by the centrifugal compressor 31, may then be led from a discharge passage 48 to apparatus or equipment selected for deriving useful work or effect from the recompressed mixture.

Figure 8 shows an arrangement in which two units A'-A' constructed in accordance with the invention are associated cooperatively for driving a turbine B'. Air supplied to the units A'-A' for a purpose to be described is compressed by a pre-compressor C'.

The units A'-A' are of identical construction. Each includes a turbine housing generally designated 49, a rotor 50 mounted on a shaft 51, and a re-compressor 52 also mounted on the shaft 51 which extends through a converging-diverging nozzle structure 53.

55 The turbine housing 49 is equipped with an inner casing or housing 54 formed to provide an annular nozzle 55 surrounding the periphery of the rotor 50. Hot air or gas delivered to the inner casing 54 may be reheated by the introduction of 60 a combustible by means not shown.

The inner casing 54 is surrounded by an annular outer housing part 56 arranged to receive air through a passage 57, the air preferably being heated in a manner to be described. The casing 57 is formed with inner surfaces 58-59 which converge to form a neck or throat into which the nozzle 55, referred to above, discharges. On the discharge or downstream side of the rotor 50, the housing 56 is formed with a surface 60 which converges toward the axis of the turbine and extends downstream with respect to the turbine rotor so as to merge with the throat of the nozzle structure 53, which is constituted by the surface 60, the throat 61, and a diverging section 62. A straight section 63 is interposed

between the diverging section 62 and the re-compressor 52.

In this arrangement, as in the arrangement shown in Figure 1, the turbine rotor periphery is disposed substantially at the throat or neck of a convergent-divergent passage provided by the converging surfaces 58—59 and the diverging surfaces 60, previously referred to, and 64, the latter being constituted by the downstream side of the rotor 50 itself.

Downstream of the rotor 50, the turbine housing 49 is formed with a toroidal chamber 65 having an inlet connection 66 through which air, pre-compressed by the equipment C' and cooled by a heat exchanger 67, is introduced. The radially inner part of the wall of the chamber 65 is provided with a passage or slot 68 which is arranged similarly to the slot 25 shown in Figure 1. The continuation of extension of the downstream wall or surface of the slot 68 merges with the surface 60 and the throat 61 of the converging-divergent nozzle 53.

In operation, air pre-compressed by the equipment C' is delivered through the passage 66 and heat exchanger 67 to the toroidal passage 65. This air, heated by the pre-compression, is cooled in passing through the heat exchanger 67, giving up heat to the air or gas flowing in through the passage 57 to the interior of the turbine housing section 56. The hot air and gas mixture discharged from the housing section 56 and the interior casing 54 through the nozzles 55 impinges on the rotor 50, driving the latter and operating the re-compressor 52. Air flowing from the toroidal chamber 65 through the slot 68 and in the direction indicated by the arrows in Figure 8 increases the velocity and hence lowers the pressure of the air and gas mixture in the throat 61 of the converging-divergent nozzle structure, thereby producing a reduced pressure zone immediately downstream of the turbine rotor 50, and thus increasing the inlet-discharge pressure differential.

The mixture of air and gas re-compressed by the supplemental compressor 52 acts upon the turbine B' so as not only to operate the pre-compressor C', but also to provide useful work. As shown in Figure 8, both units A'—A' operate in connection with the single precompressor C' and turbine B', the total power delivered to the latter being the sum of the power outputs of the units A'—A'.

Figure 9 illustrates schematically an axial flow turbine construction embodying the invention. In general, the construction includes a housing 69, and a rotor 70 equipped with peripheral blades 71 through which the hot air or gas flows parallel to the axis of rotation.

The hot air or gas may be introduced through an inlet opening 72 so as to flow into a chamber 73 shown above the rotor 70 in Figure 9. The chamber 73 is defined by wall sections 74 and 75 which converge to form a neck or throat 76 at the zone of the rotor blades 71. Downstream of the blades 71 are casing walls 77 and 78 defining a generally annular discharge passage or chamber 79. The walls 78 first are divergent with respect to the wall 77, and then converge so as to merge with the throat or neck 80 of a converging-divergent nozzle structure 81 constituted by the wall section 78, the throat or neck 80, and a divergent section 82.

A separate chamber 83 surrounds the convergent-divergent wall 78, and is adapted to receive

compressed air or gas through openings 84—84 from a compressor which may be similar to the compressor 9 shown in Figure 1 and the compressor 52 shown in Figure 8. The compressor may be driven by the shaft 85 of the turbine rotor 70.

The wall sections 78 are formed with slots 86 arranged similarly to the slots 25 shown in Figure 1. Thus, the continuations of the downstream sides or surfaces of the slots 86 merge with the throat 80 of the convergent-divergent nozzle structure 81. By virtue of this arrangement, a zone of reduced pressure is created immediately downstream of the turbine blades 71, or, otherwise stated, the inlet-discharge pressure differential is increased.

The constructions illustrated by way of example embody the invention in preferred forms, but it is intended that the disclosure be illustrative rather than definitive, the invention being defined in the claims.

What I claim is:

1. In apparatus for converting heat energy contained in a gas into work, a gas engine comprising a stator, a movable element therein drivable by said gas, a gas inlet in said stator through which gas is supplied to drive said element, and an outlet in said stator; a converging-diverging nozzle, said outlet being defined by a section which converges so as to merge with the throat of said converging-diverging nozzle; annular nozzle means extending through said converging-diverging nozzle having one surface which defines said annular nozzle means continued to form the wall of said throat of said converging-diverging nozzle; a supplemental compressor for re-compressing the gas discharged through said converging-diverging nozzle; and means for directing gas to flow through said other nozzle means into said converging-diverging nozzle and through said throat thereof in a direction away from said outlet-defining section to thereby create in said throat and consequently in said outlet a region of reduced pressure.

2. In apparatus for converting heat energy contained in a gas into work, a gas engine comprising a stator, a movable element therein drivable by said gas, a gas inlet in said stator through which gas is supplied to drive said element, and an outlet in said stator; a converging-diverging nozzle, said outlet being defined by a section which converges so as to merge with the throat of said converging-diverging nozzle; annular nozzle means extending through said converging-diverging nozzle having one surface which defines said annular nozzle means continued to form the wall of said throat of said converging-diverging nozzle; means for directing gas to flow through said other nozzle means into said converging-diverging nozzle and through said throat thereof in a direction away from said outlet-defining section to thereby create in said throat and consequently in said outlet a region of reduced pressure; means driven by said engine for pre-compressing the gas before it is delivered to said inlet; means for conducting part of the gas away from said inlet and to said other nozzle means for flow therethrough into said converging-diverging nozzle throat; heat exchange means through which air is passed for cooling the pre-compressed gas; and means for delivering a portion of the air from said heat exchange means for mixing with the gas supplied for driving said element and for delivering another portion of said air from said heat exchange means to said other

nozzle means for flow therethrough into the throat of said converging-diverging nozzle.

3. In apparatus for converting heat energy contained in a gas into work, a gas turbine including a stator, a rotor therein, a gas inlet in said stator, means for directing gas from said inlet to impinge on said rotor for driving the latter, and an outlet in said stator coaxial with and immediately adjacent said rotor; a converging-diverging nozzle coaxial with said rotor, said outlet being defined by a section which converges from a zone relatively near the periphery of said rotor inwardly towards the rotor axis and away from said rotor and merges with the throat of said converging-diverging nozzle; annular nozzle means extending through said converging-diverging nozzle having one surface which defines said annular nozzle means continued to form the wall of said throat of said converging-diverging nozzle; and means for directing gas to flow through said other nozzle means into said converging-diverging nozzle and through the throat thereof in a direction away from said outlet-defining section to thereby create in said throat and consequently in said outlet a region of reduced pressure.

4. Apparatus as set forth in claim 3 including means for pre-compressing the gas before it is delivered to said inlet.

5. Apparatus as set forth in claim 3 including means for pre-compressing and cooling the gas before it is delivered to said inlet.

6. Apparatus as set forth in claim 3 including means for conducting part of the gas away from said inlet and to said other nozzle means for flow therethrough into said converging-diverging nozzle throat.

7. Apparatus as set forth in claim 3 in which said outlet defining section forms a part of said stator and also forms the converging part of said converging-diverging nozzle.

8. Apparatus as set forth in claim 3 including a supplemental compressor for re-compressing the gas discharged through said converging-diverging nozzle.

9. Apparatus as set forth in claim 3 including means driven by said turbine for pre-compressing the gas before it is delivered to said inlet; means for conducting part of the gas away from said inlet and to said other nozzle means for flow therethrough into said converging-diverging nozzle throat; heat exchange means through which air is passed for cooling the pre-compressed gas; and means for delivering a portion of the air from said heat exchange means for mixing with the gas impinging on said rotor and for delivering another portion of said air from said heat exchange means to said other nozzle means for

flow therethrough into the throat of said converging-diverging nozzle.

10. Apparatus as set forth in claim 3 in which the means for directing gas to impinge on the said rotor comprises annularly extending nozzle means, said apparatus including further: means for pre-compressing the gas before delivery thereof to said annularly extending nozzle means; air passage means for conducting air in heat exchanging relation to the pre-compressed gas; and still further nozzle means for discharging air from said air passage means to impinge on said rotor intermixed with the gas discharged by said annularly extending nozzle means.

11. In apparatus for converting heat energy contained in a gas into work, a gas turbine including a stator, a rotor therein, a gas inlet in said stator, means for directing gas from said inlet to impinge on said rotor for driving the latter, and an outlet in said stator coaxial with and immediately adjacent said rotor; and a converging-diverging nozzle coaxial with said rotor, said outlet being defined by a section which converges from a zone at the periphery of said rotor inwardly towards the rotor axis and axially away from said rotor and merges with the throat of said converging-diverging nozzle, said converging outlet section being the converging part of said converging-diverging nozzle, whereby a region of low pressure is created in said throat immediately downstream of said turbine rotor.
